DESIGN FOR A DRESS

Theresa M. Fritz, New York, N. Y.

Application February 3, 1939, Serial No. 82,749

Term of patent 3½ years

To all whom it may concern:

Be it known that I, Theresa M. Fritz, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the specific dress disclosed of the specific appliqued circles on the front and sleeve portions as shown.

The small circles which entwine the larger ones consist of gathered material.

I claim:

The ornamental design for a dress, substantially as shown and described.

THERESA M. FRITZ.
